CLAIM

The ornamental design for a golf ball, as shown and described.

DESCRIPTION

FIG. 1 is a front-bottom perspective view of a golf ball according to our new and ornamental design;

FIG. 2 is a front-top perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof; and,

FIG. 8 is a left side elevation view thereof.

The broken lines illustrate portions of the golf ball that form no part of the claim.
